SCREENED WINDOW

Kurt H. Feige, Chicago, Ill.

Application August 14, 1935, Serial No. 36,125

6 Claims. (Cl. 156—39)

This invention relates to window screens of the roller type. Among the salient objects of the invention are to provide a construction which may be readily applied to existing windows with a minimum of alterations; to produce a construction which may be incorporated in either metal or wood sash; to render possible the use of an ample length of screen fabric; to devise a construction which shall not interfere with the proper closing of the window; to provide means for holding the edges of the screen against a suitable surface to prevent flies from passing around the edges; and in general to provide a neat, simple, inexpensive and efficient screened window.

In the accompanying drawing:

Figure 1 is a perspective view of a screened window embodying the features of my invention, the view being taken from within the room.

Fig. 2 is a fragmental vertical sectional view through the window frame, the lower sash and the screen, the lower sash being shown in raised position, as in Fig. 1.

Fig. 3 is a fragmental elevation looking from within the room, as indicated by the dotted line 25 3—3 of Fig. 2.

Fig. 4 is a horizontal sectional view taken in the plane of dotted line 4—4 of Fig. 2.

Fig. 5 is a fragmental sectional view taken in 30 the plane of line 5—5 of Fig. 2.

Fig. 6 is a fragmental perspective view showing a yielding mounting for the screen roller.

Fig. 7 is a fragmental perspective view of the lower left-hand corner of the lower sash, as 35 viewed from within the room.

In the drawing, 1 denotes the window frame, the window sill or ledge being indicated at 2. The upper sash is not shown in the drawing, but it is intended to be adjustable up and down, if 40 desired, along the vertical stops or guides 3 (Figs. 2 and 4). In Fig. 2 the path of movement of the upper sash is at the right of the stop 3.

The lower sash is herein shown as an ordinary wooden sash with the lower rail replaced 45 with a rail embodying features of my invention. The sash comprises the usual wooden stiles 4 and upper rail 5 (Figs. 1, 3 and 7). The lower rail 6 (Fig. 7) is formed of sheet metal and takes the place of the usual wooden lower rail of the lower 50 sash. The sheet-metal lower rail 6 is formed of sheet metal bent to provide a front wall 7, a rear or outer wall 8 and an upper edge wall 9, said edge wall being bent to form a seat 10 for the lower edge of the window pane 11. The bottom 55 wall 12 of the rail 6 is formed of a separate piece of sheet metal bent to fit snugly between the walls 7 and 8. The bottom wall 12 has an upstanding flange 12a at the sides and ends (see Figures 2 60 and 6) and is removably secured in place in any

preferred way, as, for example, by friction. The ends 13 of the lower rail 6 are formed from sheet metal (Figs. 4, 6 and 7).

In the ordinary wood sash the rails lie between the stiles. In applying my invention to such a sash, the lower rail is removed, the stiles shortened by sawing off the lower ends thereof, and slots 15 (Fig. 3) formed in the shortened ends of the stiles.

The end portions of the metal rail 6 are then 10 secured to the lower ends of the wooden stiles 4 by means including an upwardly extending web or flange 14 formed on each end of the rail 6, said flanges extending into the slots 15 (Fig. 3) in the lower ends of the stiles 4 and being secured 15 in place by means of screws 16 (Figs. 1, 3 and 7) extending into the stiles and through said flanges.

Within the hollow rail 6 is rotatably mounted a 20 spring-actuated roller upon which is wound a sheet of wire cloth, textile fabric or other desired flexible material, the outer lower edge of said fabric being detachably secured to the window frame at the window sill. The roller is indicated at 17 in Figs. 4 and 7. It consists of a tube having plugs 18 in its opposite ends, said plugs being 25 rotatably mounted upon a pivot rod 19. The ends of the pivot rod are flattened to extend non-rotatably through vertical slots 20 in the end walls 13 of the rail 6. The roller is yieldingly 30 supported within the rail 6 by means of two springs 21, one under each end of the pivot rod 19, a block 22 slidably mounted in the slot 20 being interposed between the spring and the pivot 35 rod and being connected to the spring. The lower end of the spring 21 is secured in notches 40 formed in the walls of the slot 20, as shown in Fig. 6. It will be understood that the spring mounting of the roller will allow the roller to yield in case of a sudden or violent upward tug 45 on the sash, and will also permit the ends of the roller to adjust themselves in height so as to hold the screen under even tension.

A torsion spring 23 (Fig. 4) is secured at one 45 end to the pivot rod 19 and at its opposite end to one of the plugs 18, said spring tending to revolve the roller 17 in the direction to roll up the beforementioned sheet of screen fabric. Said sheet is indicated at 24. Its upper end is attached to the roller 17. The bottom wall 12 of the rail 6 has a slot 25 therein to allow the screen 24 to extend therethrough. As herein shown, the lower edge of the screen 24 is secured to a rod 26 (Fig. 5), said rod comprising a spring-pressed end-section 27. The ends of the rod 26 project 50 beyond the vertical edges of the screen 24 into position to be engaged by the notched lower ends of two leaf springs 23 secured at their upper ends to the window frame 1. It will be seen that by contracting the rod 26 and sliding it with refer- 55 60

ence to the screen 24 and by forcing the lower ends of the leaf springs 28 apart, the screen may be freed from its connection with the window frame, whereupon the spring 23 will act to roll up the screen and hold the lower end thereof within a recess 29 formed in the lower side of the bottom wall 12 of the rail 6.

If it should be desirable to remove the roller 17 from the window, the lower wall 12 may be removed, the springs 21 disengaged from the walls of the slot 20, and said springs, the blocks 22 and the pivot rod 19, with the roller 17 thereon, removed from the rail 6.

Means is provided to hold the edge portions of the screen 24 in contact with the stop 3. Herein I have shown devices secured to opposite sides of the window frame which are duplicate, except that one is made right-hand and the other left-hand. These devices include a sheet-metal casing or tube 30 which is rectangular in cross-section and which is secured to the inner side of the window frame, said casing constituting a window stop that takes the place of the usual stop located at the inner side of the path of movement of the lower sash. A suitable number of spring arms 31 are secured at one end within the tubular stop 30, and project through vertical openings 32 (Figs. 2 and 3) in the edge of the stop 30 which is adjacent to the path of movement of the lower sash. The free ends of one or more of the spring arms 31 bear against the vertical edge portions of the screen 24 when the lower sash is raised. When the lower sash is closed, it deflects the free ends of the spring arms 31 forwardly out of its path.

If desired, means may be provided for manually operating the spring arms 31 into and out of their operative position. Herein I have shown a rod 33 having lugs 34 (Figs. 3 and 4) that project into loops 35 on the spring arms 31. The rod 33 extends vertically within the tubular stop 30 and its upper end is bent, as shown in Fig. 3, to extend into a slot 36 in the tubular stop. The upper and lower ends of the slot 36 extend at an angle so that when the bent upper end of the rod 33 is placed therein the rod will be held in either its upper or its lower position, as the case may be. To the upper bent end of the rod 33 is secured a handle 37.

Means may be provided for latching the lower sash in raised position in various elevations. Herein I have shown a series of openings 38 in the wall of the tubular slot 30 adjacent to the lower sash, each of which is adapted to receive the angular end 39 of a leaf spring 40 which is secured to the front wall 7 of the rail 6 at 41. 42 is a stud secured to the spring latch 40, said stud projecting from the wall 7 adjacent to one of the handles 43 secured to the rail 6 of the lower sash, so that when the operator desires to move the sash up or down the thumb of the hand that engages the handle 43 may be used to depress the pin 42 to disengage the angular end of the leaf spring 40 from the opening 38 with which it may be engaged.

It will be seen that I have provided very simple means whereby a window screen of the roller type may be readily applied to an ordinary window, the metal rail 6 being substituted for the wood rail of a wooden sash, and the tubular metal stops 30 with their appurtenances being substituted for the usual wooden stops at the inner side of the lower sash.

The metal rail 6, with the attaching portions

14, the roller 17, its self-adjusting bearings 22, the screen 24 and the rod 26—27, constitutes a replacement unit which may be readily substituted for the rail of an ordinary sash.

The invention is not limited to use with wooden sash, since obviously the rail 6 may be incorporated in a metal sash.

It has been proposed to apply a window screen of the roller type by attaching a casing containing such a screen to the lower edge of the usual lower rail of the lower sash, but such an arrangement is impracticable, since it prevents the lower sash from being completely closed, a gap remaining between the upper portion of the lower sash and the lower portion of the upper sash.

It has also been suggested that a screen roller be housed within the wooden rail of a sash, but such a construction is not practical, because the wood rail cannot be hollowed out sufficiently to provide a chamber wide enough to contain the roller and an adequate length of screen fabric wrapped around it.

Although I have shown the invention as embodied in a window having a screen below the lower sash, it will be apparent that the same principle may be utilized in screening the space above the upper sash, when the latter is lowered.

For the sake of brevity, the word "screen" is used in the following claims to denote a sheet of fabric serving the purpose of a screen or filter.

I claim as my invention:

1. In a window having a vertically movable sash, a roller carried by the sash, and a screen attached at one end to said roller and at its other end to the frame; a series of spring arms mounted on the frame along the path of movement of the sash to press against a vertical edge of the screen when the sash is moved to extend the screen, and manually-operable means for displacing said arms out of the path of the sash.

2. In a window, a screen, a series of spring arms located on the frame of the window and arranged to bear at their free ends against the screen, and means for moving said arms away from the screen, said means comprising a rod connected to said arms, a handle on said rod, and means on the frame to hold said rod in a plurality of positions.

3. A tubular window stop formed of sheet metal and having an opening in its inner edge, and a spring arm attached at one end to said stop and projecting through said opening.

4. In combination, a window sash, and means for rotatably mounting a spring screen roller in the sash, said means comprising springs yieldingly supporting the ends of the roller for independent adjustment under the tension of the screen.

5. A unit comprising a sash rail having members at its ends for attachment to stiles, said rail being adapted to house a spring roll screen, and having a one-piece separate bottom wall which is slotted to allow said screen to pass therethrough, said screen having a rod on the free end thereof, said wall having a longitudinal recess to house said rod, said wall being frictionally secured in place in the rail.

6. A unit comprising a sash rail having a roller screen housed therein, said rail having in its ends vertical slots, said roller screen having pivots extending into said slots, and means for yieldingly supporting said pivots in said slots.
